UNITED STATES PATENT OFFICE.

THOMAS SPENCER MILLER, OF SOUTH ORANGE, NEW JERSEY.

CONVEYING APPARATUS.

SPECIFICATION forming part of Letters Patent No. 691,911, dated January 28, 1902.

Application filed June 9, 1900. Serial No. 19,671. (No model.)

To all whom it may concern:

Be it known that I, THOMAS SPENCER MILLER, of South Orange, Essex county, New Jersey, have invented a new and useful Improvement 5 in Conveying Apparatus, of which the following is a specification.

This invention consists in improvements on the apparatus shown in my Letters Patent of the United States No. 637,143, dated November 14, 1899.

In the accompanying drawings, Figure 1 is a side view of two ships equipped with my improvements, the collier being in tow of the battle-ship. Fig. 2 is a detail of the apparatus 15 carried by said ships. Fig. 3 is a side view of two ships equipped with my improvements, which differs from Fig. 1 in that the battle-ship is in tow of the collier. Fig. 4 is a detail of the apparatus of Fig. 3. Fig. 5 is a detail 20 showing the elevator employed in both Figs. 1 and 3. Fig. 6 is a cross-section of said elevator. Fig. 7 is a detail showing the elevating-carriage with the loaded bags hanging thereon.

25 A is the receiving-ship to which coal, provisions, mail, or other commodity is to be delivered from the ship B.

C is a rope connecting the two ships.

The ship A of Fig. 1 and the ship B of Fig. 30 3 are provided with propelling mechanisms, so that while the apparatus is in operation the propelling mechanism on one ship causes it to pull the other ship by the pull-line C. If, as is preferable, neither ship is anchored, 35 this pulling action will tow the pulled boat along, but otherwise if the pulled boat is at anchor. In either case, however, the propelling of one of the ships in a direction away from the other, to which it is attached by the 40 pull-line C, will serve to maintain as uniform a distance between the ships as the elements will permit.

D is a load-support from which the load is suspended while in transit. In the particular 45 form of load-support shown in the drawings it is a carriage provided with wheels that run upon a rope across the span.

E is a transit-rope extending from an elevated support F on one boat to an elevated 50 support G on the other. If the transit-motor hereinafter described is located wholly off of the receiving-ship, as I prefer and as here-

inafter particularly described, the transit-rope E will consist of two branches, one of which, e' , extends from the elevated support 55 on the delivery-ship to and around a sheave g on the elevated support of the receiving-ship, and the other of which branches, e^2 , extends back to the elevated support F on the delivery-ship and thence to the elevated support F' on the delivery-ship. The two branches e' and e^2 are preferably substantially parallel. The transit-rope E is fastened to the load-support D in some manner suitable for moving the load-support across the span, the preferable method being by such a gripping engagement as is shown in said Patent No. 637,143. The transit-motor consists of the two rope-drums h' , which acts as the forward actuator, and the drum h^2 , which acts as the 60 backward actuator. Each of these drums is impelled by a friction-clutch, and the speed of the friction-clutch driving the forward actuator h' may be varied independently of the speed of the friction-clutch driving the backward actuator h^2 . This independence of speed variation is accomplished in the example 65 shown in the drawings by having said actuators run by separate motors h^3 and h^4 . I prefer that each of the rope-drums h' and h^2 and 70 the friction mechanism by which it is propelled and the means of controlling such friction mechanism shall be substantially the same as that shown for the friction-drum h^2 in said Patent No. 637,143. The support F 75 may be provided with the sheaves f' and f^2 , over which, respectively, the branches of the transit-rope E may extend. One branch extends down to the forward actuator h' , and the other extends over the sheave f^3 and 80 then down to the backward actuator h^2 .

In order to better insure the uniform elevation of the load-carriage during its transit, I prefer to combine with the parts above described a supporting - rope L, connecting 85 through a spring l with a towing-ship, thence extending over a support l' on the towing-ship just above the upper branch e^2 of the transit-rope, thence extending under the sheave l^2 on the upper portion of the load-support, thence 90 extending over the support l^3 on the towed ship just above the support for the upper branch of the transit-rope, thence extending over the stern of the towed boat and connect- 95 100

ed at its end with a sea-anchor M, trailing in the water behind the towed boat.

K is the elevating-carrier, and k is the fall-rope therefor, extending over sheaves k' and 5 k² on the support F, from which the load starts across the span. The elevating-carrier contains fixed fingers k³, upon the horizontal tips of which is supported the bale k⁴, from which the bags n' n² n³ are supported.

10 O is a tubular elevator-way extending from the keel of the vessel to above the level of the ropeway at the support F. This forms a complete inclosure for the bags while being elevated from the bottom of the vessel to the 15 point at which they are delivered to the load-support. It is provided with openings o², o³, and o⁴, one between each two decks of the vessel, so that the elevating-carrier can receive its load from either deck.

20 o and o' are guideways on opposite sides of the elevator-tubing, which serve to guide the elevating-carrier K in its transit.

P is an opening into which the cables L, e', and e² enter, so that the load-support D also 25 passes into said opening P in such manner that its supporting-finger d enters under the bale k⁴ as the same is held by the fingers k³ of the elevating-carrier K at the top of its ascent.

30 p' and p² are deflectors whereby the load-carrier D as it enters the opening P is guided to the center of said opening, so that its horn d properly engages with the bale k⁴. In order to permit the bags to pass out through the 35 opening P, these deflectors are respectively pivoted on opposite sides of the opening P and are held in the position shown in full lines in Fig. 6 by the springs q' and q², which are so constructed as to permit the deflectors 40 to swing outward into the position shown in dotted lines in Fig. 6 when the bags are making their exit through the opening P.

The operation is as follows: The elevating-carrier K being at any deck in the tubular 45 elevator-way O, the operator hangs a bale k⁴, carrying bags, on the fingers of the elevating carrier. Then the same is elevated by the fall-rope k to a position such that the fingers d of the load-support in returning enter the 50 bale k⁴. The fingers of the load-support are constructed as described in said Patent No. 637,143, so that as the load-support starts on its outward journey the bale k⁴ is retained by the fingers d and pulled bodily off of the 55 fingers k³. As the load-support is on its outward journey it is impelled forward by the forward actuator h', but the backward actuator h² is constantly tending to haul it backward and is only prevented from doing so by 60 the fact that the friction of the forward actuator is stronger than the friction of the backward actuator, causing the latter friction to slip.

In order that the apparatus may meet the 65 varying conditions due to the lurching of the ships with the greatest certainty and quick-

ness, I construct and operate the outward transit-actuator so as to run at a speed adapted to actuate the transit-rope at a speed greater than the relative motion between said boats 70 due to the waves. The maximum speed at which the distance between supports upon the two ships may be expected to decrease from waves or other causes may be taken as five feet per second. The forward transit-actuator 75 will be speeded so as to haul in the transit-rope at a rate in excess of ten feet per second—say, for example, at the rate of fifteen feet per second. Now suppose during the transit of a load that the ships lurch toward 80 each other at the maximum rate of five feet per second. Since there are two lengths of the rope E stretched between the ships, this will produce a slack in the rope at the rate of ten feet per second; but the rate at which this slack 85 is produced is less than the fifteen feet per second of the forward transit-drum, and consequently the forward transit-drum takes up this slack as fast as produced, with five feet per second speed to spare, and the normal elevation 90 of the load is maintained. Now suppose that the ships lurch away from each other. This will demand a greater length of rope on the span, which will be supplied by the backward transit-drum (which for the time being 95 is acting as the tension-drum) by causing it to pay-out at a speed accelerated to any extent demanded. Therefore it will be seen that under all possible conditions the apparatus will maintain the load at substantially 100 a normal elevation and relieve itself automatically from undue strain. As the operator of the forward transit-actuator sees that the load-carriage is approaching the end of its outward journey and is about to strike 105 the abutment by which it is caused to drop its load onto the receiving vessel, it is desirable that he should slacken its speed, and since the speed of the actuator of the drum h' may be varied independently of the speed 110 of the actuator-drum h² the operator will permit the drum h² to continue at a constant speed, and therefore a speed sufficient to take care of any slack that may result from the lurching of the vessels toward one another, 115 while he reduces the speed of the actuator of h', so as to bring the load-carriage gently against its abutment.

Should for any reason the transit-rope E fail to properly perform its function in maintaining the constant elevation of the load-support D, the supporting-rope L will always supply the needed support, whatever may be the position of the load. This supporting-rope L also serves to prevent the overturning 125 of the load-carriage and, if desired, will enable a much greater load to be transported across the span for a given engine-power.

I claim—

1. In combination, a pulling-boat, a pulled 130 boat, a pull-rope, a transit-rope, a load-support moved thereby, a rope-drum connected

with each end of said transit-rope, and an independent motor for actuating each of said drums.

2. In combination, a pulling-boat, a pulled boat, a pull-rope, a transit-rope, a load-support moved thereby, an actuator of said transit-rope, a tension device acting upon said transit-rope, a supplemental supporting-rope and a tension device acting upon said supplemental supporting-rope.

3. In combination, a pulling-boat, a pulled boat, a pull-rope, a transit-rope extending from one boat to the other and back again, a load-carriage running upon one branch of said transit-rope and moved by the other branch thereof, an actuator of said transit-rope, a tension device acting upon said transit-rope, a supplemental supporting-rope and a tension device acting upon said supporting-rope.

4. In combination, a pulling-boat, a pulled boat, a pull-rope, a transit-rope, a load-support moved thereby, a rope-drum connected with each end of said transit-rope, independently-controllable means for actuating each of said rope-drums, a supplemental supporting-rope and a tension device acting upon said supplemental supporting-rope.

5. In combination, a pulling-boat, a pulled boat, a pull-rope, a transit-rope, a load-support moved thereby, a rope-drum connected with each end of said transit-rope, independently-controllable means for actuating each of said rope-drums, a supplemental supporting-rope and a sea-anchor connected with said supporting-rope.

6. In combination, a pulling-boat, a pulled boat, a tow-line connecting the two boats, a trackway-cable extending from the pulling-boat over and to the rear of the pulled boat, guiding-supports for the trackway-cable upon the pulled boat, a sea-anchor on the rear of the trackway-cable, and means for transferring loads between the boats upon the trackway-cable.

7. In combination, a pulling-boat, a pulled boat, a tow-line connecting the two boats, a trackway-cable extending from the pulling-boat over and to the rear of the pulled boat, guiding-supports for the trackway-cable upon the pulled boat, a sea-anchor secured to the trackway-cable behind the pulled boat, a yielding connection of the trackway-cable with the pulling-boat, and means for transferring loads between the two boats over said trackway-cable.

8. In combination, a pulling-boat, a pulled boat, a tow-line connecting the boat, a trackway-cable extending from the pulling-boat over and to the rear of the pulled boat, guiding-supports for said cable upon the pulled boat, a sea-anchor upon said cable astern of the pulled boat, a carrier adapted to travel

upon the trackway-cable between the boats, a traversing-cable connected with said carrier, and actuators for said traversing-cable.

65

9. The combination with a ropeway, a load-carrier and means for moving said carrier lengthwise of said ropeway, of a conveying-tube leading to the ropeway, and a load-conveyer movable in said tube and adapted to present the load to the load-carrier.

10. The combination with a ropeway, a load-carrier and means for moving the load-carrier lengthwise of said ropeway, of a conveying-tube leading to the ropeway and having a load exit-opening adjacent the ropeway, and a load-conveyer movable in said tube and adapted to present the load to the load-carrier.

11. The combination with a ropeway, a load-carrier and means for moving the load-carrier lengthwise of said ropeway, of a conveying-tube leading to and inclosing one end of the ropeway and having an opening permitting the passage of the carrier and its load, and a load-conveyer in said tube adapted to present the loads to the carrier.

12. In combination a ropeway having a carrier and means for traversing the carrier thereon, a hoisting-tube leading up to the ropeway and having an exit-opening beneath the ropeway, and a load-hoist operating within said tube and adapted to present the load to the ropeway-carrier.

13. In combination a ropeway having a carrier and means for traversing the carrier thereon, a hoisting-tube leading up to the ropeway and having an exit-opening beneath the ropeway, a load-hoist operating within said tube and adapted to present the load to the ropeway-carrier, and swinging sectors partly closing the exit-opening in the tube and adapted to properly guide the load-carrier upon its entrance therein.

14. In combination a ropeway having a carrier and means for traversing the carrier thereon, a hoisting-tube leading up to the ropeway and having an exit-opening beneath the ropeway, a load-hoist operating within said tube and adapted to present the load to the ropeway-carrier, said hoist having a load-receiving hook extending toward the carrier in its approach, and the load-carrier having an oppositely-extending hook adapted to engage and remove the load from the hoisting device.

In testimony whereof I have signed my name to this specification in the presence of two subscribing witnesses.

THOMAS SPENCER MILLER.
